[57] CLAIM

The ornamental design for a beverage container, as shown and described.

DESCRIPTION

FIG. 1 is a front elevation of a beverage container showing my new design, the rear elevation is the same except for the threading on the neck;

FIG. 2 is a side elevation thereof, the opposite side elevation is the same except for the threading on the neck;

FIG. 3 is a top view thereof;

FIG. 4 is a bottom view thereof;

FIG. 5 is a side elevation of a second embodiment of the beverage container, the opposite side elevation is the same except for the threading on the neck;

FIG. 6 is a front elevation of the second embodiment, the rear elevation is the same except for the threading on the neck;

FIG. 7 is a top view thereof; and,

FIG. 8 is a bottom view thereof.
